Primary Examiner — Michelle E. Wilson*Assistant Examiner* — Charles Hwang(74) *Attorney, Agent, or Firm* — Kasha Law LLC; John R. Kasha; Kelly L. Kasha(57) **CLAIM**

The ornamental design for an electric vehicle charger as shown and described.

DESCRIPTION

FIG. 1 is a front perspective view of a socket type of an electric vehicle charger, in accordance with the present invention.

FIG. 2 is a front view of the electric vehicle charger of FIG. 1, in accordance with the present invention.

FIG. 3 is a rear view of the electric vehicle charger of FIG. 1, in accordance with the present invention.

FIG. 4 is a top view of the electric vehicle charger of FIG. 1, in accordance with the present invention.

FIG. 5 is a bottom view of the electric vehicle charger of FIG. 1, in accordance with the present invention.

FIG. 6 is a right side view of the electric vehicle charger of FIG. 1, in accordance with the present invention; and,

FIG. 7 is a left side view of the electric vehicle charger of FIG. 1, in accordance with the present invention.

The broken line showing of the electric vehicle charger is included for the purpose of illustrating portions of the article and forms no part of the claimed design.

1 Claim, 5 Drawing Sheets(56)
